H. E. STITT,
BUILDING CONSTRUCTION,
APPLICATION FILED JULY 3, 1918.

1,433,490.

Patented Oct. 24, 1922.

UNITED STATES PATENT OFFICE.

HARRY E. STITT, OF EAST CLEVELAND, OHIO.

BUILDING CONSTRUCTION.

Application filed July 3, 1918. Serial No. 243,115.

To all whom it may concern:

Be it known that I, HARRY E. STITT, a citizen of the United States, and a resident of East Cleveland, county of Cuyahoga, and 5 State of Ohio, have invented a new and useful Improvement in Building Constructions, of which the following is a specification, the principle of the invention being herein explained, and the best mode in which I have 10 contemplated applying that principle so as to distinguish it from other inventions.

In modern building construction, particularly for factories, much progress has been made in standardizing the design of the 15 frame. The latter is almost invariably fabricated of steel, and by keeping in stock the parts of which such frames are made, buildings of standardized type may be much more quickly assembled and erected than where 20 the parts have to be specially fabricated.

The object of the present invention is to provide more generally interchangeable structural units than are at present in use in buildings of this type, that is units that may 25 be utilized in buildings not only of any length, but of various widths. At the same time the number of parts or structural elements which it is necessary to keep in stock is correspondingly reduced, thus enabling 30 the builder to meet varying demands with a minimum investment in the way of stock. To the accomplishment of the foregoing and 35 related ends, the invention, then, consists of the means hereinafter fully described and particularly pointed out in the claims.

The annexed drawing and the following 40 description set forth in detail certain structure embodying the invention, such disclosed means constituting, however, but one of various mechanical forms in which the principle of the invention may be used.

In said annexed drawing:—

Fig. 1 is a transverse section, more or less diagrammatic in character, through a building embodying my present improvements; Fig. 2 is a longitudinal section of a portion of such building, the plane of the section being indicated by the line 2—2, Fig. 1; and Fig. 3 is a transverse section of a portion of the building as shown in Fig. 1, more fully showing the details of construction.

My present improved building construction is composed of four essential and pri-

mary structural parts, viz, a column 1, a truss 2, a monitor frame 3, and bracing members 4 and 5, for use between columns, lengthwise of the building.

All of the columns are alike, in that they are detailed so as to connect to either end of the standard trusses presently to be described, being made of the same length, the only variation which may possibly be required being in the matter of strength, where a special load is to be imposed.

The trusses, which are in general of familiar construction, have their top chords sloping down in two directions from a midpoint thereon. Such trusses will be made up in different lengths, for example forty feet, fifty feet and sixty feet long respectively, 70 an adequate number of each length being carried in stock. Irrespective of their length, all such trusses will have the same depth on all of their ends, so that they may be interchangeably connected to the standard column previously described. In addition to thus having their ends of uniform depth, all the trusses will have the slope of their top chords uniform, so that the only other difference between trusses of different 80 lengths will be that of height at midpoint and strength.

The monitor utilized in connection with the foregoing, is of the so-called valley type, being designed to set in the obtuse angle between terminally abutting trusses. Since 85 the height of the ends of the latter is uniform, as well as the slope from such ends, it will be seen that a stock monitor frame may be utilized in combination with trusses, 90 whether the latter be of the same or different lengths.

The manner in which a building composed of standardized elements, as just described, may be assembled in multiple, is well shown 95 in Fig. 1, where at the left I have illustrated two trusses 2 of the same length in combination with a standard monitor frame 3, and at the right such a monitor frame combined with trusses of different lengths, as indicated in dotted outline. As further shown 100 in Fig. 2, the height of the columns being uniform, as well as the depth of the ends of the trusses, the bracing 4, 5 employed between the columns longitudinally of the 105 building, whatever its form, may be of

standardized construction, since the columns will of course be uniformly spaced.

Fig. 3 illustrates the manner in which the roof 6 over the exposed portion of the trusses, as well as the roof 7 over the monitor 3, is supported therefrom, and at the same time shows the side wall 8, which incorporates the corresponding row of columns 1.

It will be obvious that the building may be continued lengthwise indefinitely, while transversely it may consist simply of an assemblage of two standard trusses with monitor frame, or of as many more such trusses of varying widths and additional monitor frames as is necessary to give the requisite overall width. Furthermore, with a minimum number of standard fabricated trusses of the construction described, it is possible to secure a building, whether of one or more units, of almost any desired width. Thus a combination of two fifty foot trusses will provide a building one hundred feet wide; while a forty and fifty foot truss will provide one ninety feet wide, and so on. Irrespective of the length of trusses utilized in any particular building, the standard monitor frames will interfit without alteration, and the same is true of the bracing longitudinally of the building. These desirable results follow from the provision of the trusses with uniform depth at ends and uniform slope of top chords up from such ends and towards the center or midpoints of the trusses.

It will be understood of course that while my improved building construction has been described and shown as fabricated out of steel, it is in no sense limited to the use of any particular material, but the columns, trusses, and in fact all the various parts thereof, may be made out of wood, for example, if for any reason found desirable.

Moreover, while the advantages flowing from my improved construction are fully evident where the building is of such a width as to require two or more trusses placed end to end transversely of such building, the use of interchangeable elements, and particularly of trusses of the character described, in a building having initially the width of but a single truss, is highly advantageous, since it is possible to add additional trusses to such building on either side and correspondingly extend its width. This flexibility in my construction enables the builder to adapt the building to the needs of a growing enterprise by extending it not merely longitudinally, but also laterally, wherever there is a demand for more space, without necessitating the relocation of the departments housed in the building.

Other modes of applying the principle of my invention may be employed instead of the one explained, change being made as regards the construction herein disclosed, pro-

vided the means stated by any of the following claims or the equivalent of such stated means be employed.

I therefore particularly point out and distinctly claim as my invention:

1. In a standard building construction, the combination with uniform interchangeable columns having supporting elements uniformly spaced on opposite sides of their upper ends, of stock truss frames comprising straight bottom chords, inverted V-shaped top chords of constant angle, and interconnecting members, said truss frames being of uniform vertical end dimensions, but of varying span, a series of said columns 80 equally spaced longitudinally at the side walls of the building and centrally thereof, the central columns being arranged in rows 75 unequally spaced transversely, longitudinally extending connections between said central 85 columns, said truss frames being parallelly arranged in longitudinal series with their ends resting upon said supporting elements, the frames of adjacent series being of identical cross-sectional outline and of optional 90 span, and stock monitor frames of a single uniform construction including an inverted V-shaped top member and a plurality of vertical strut members, the lower ends of said strut members forming a transverse angle 95 supplementary to the transverse angle formed by two abutting truss frames.

2. In a standard building construction, the combination with uniform interchangeable columns, having uniform supporting 100 elements at their upper ends, of stock truss frames comprising straight bottom chords, inverted V-shaped top chords of constant angle, and interconnecting members, said truss frames being of uniform vertical end 105 dimensions, a series of said columns equally spaced longitudinally at the side walls of the building and centrally thereof, the central columns being arranged in rows 110 unequally spaced transversely, longitudinal series of said truss frames with their ends resting upon said supporting elements, a roof supported upon the outer inclined sections of said inverted V-shaped chords of 115 aligned truss frames and extending continuously inward and upward above the inner reversely inclined portions of said frames, and supports for said inner portion of said roof.

3. In a standard building construction, the 120 combination with uniform interchangeable columns, having uniform supporting elements at their upper ends, of stock truss frames comprising straight bottom chords, inverted V-shaped top chords of constant 125 angle, and interconnecting members, said truss frames being of uniform vertical end dimensions but of varying span, a series of said columns equally spaced longitudinally 130 at the side walls of the building and cen-

trally thereof, the central columns being arranged in rows unequally spaced transversely, longitudinal series of said truss frames of a span corresponding to the respective transverse rows of columns with their ends resting upon said supporting elements, a roof supported upon the outer inclined sections of said inverted V-shaped chords of aligned truss frames and extending continuously inward and upward above the inner reversely inclined portions of said frames, stock monitor frames of a single uniform construction connected to the V-shaped structure formed by each two adjacent truss

frames said monitor frames comprising an inverted V-shaped top member, a central and pairs of lateral vertical struts and tie bars connected to the base of said central strut, the lower terminals of said struts forming a constant angle supplementary to the angle formed by the abutting truss frames, a roof supported upon said monitor frames, and supporting elements upon the outside members of said monitor frames for supporting the inner portions of the truss frame roof sections.

Signed by me, this 28th day of June, 1918.

HARRY E. STITT.
